UNITED STATES PATENT OFFICE.

MARIE F. C. STOCKMANN, OF NEW YORK, N. Y.

WRITING MATERIAL.

987,926.

Specification of Letters Patent. Patented Mar. 28, 1911.

No Drawing.

Application filed July 30, 1910. Serial No. 574,735.

To all whom it may concern:

Be it known that I, MARIE F. C. STOCKMANN, a citizen of Germany, a subject of the Emperor of Germany, and a resident of 5 New York, county and State of New York, have invented a certain new and useful Improvement in Writing Materials, of which the following is a specification.

My invention relates to improvements in 10 writing materials for the blind, and the main object of my invention is to provide a writing material by means of which people deprived of sight may communicate between themselves or with people not deprived of 15 sight, by writing the ordinary and usual script characters, etc. By using my improved writing material any one possessed of the ordinary knowledge of writing may be able to communicate with the blind by 20 writing and using only the usual script characters.

My improvements have been described in a prior application of mine, filed January 12, 1909, Serial No. 471,862.

25 In its preferred form my improved writing material consists of a solid basic material, a drying material, water, an adhesive material, and a coloring material, so that a rather thick colored fluid material of contrasting color with the paper is produced, which, when deposited upon paper by a suitable pen will quickly dry and leave the characters raised upon the surface of the paper so that they are readily perceptible 30 to the touch and the blind may easily read them.

More specifically, the preferred composition of my improved writing material is as follows: One part sugar, one part flour, one 40 part water, one part mucilage and one part black ink. The flour acts as a basic material and the amount of sugar may be varied in order to vary the drying qualities of the material to different extents. The ink is 45 added merely to color the material so that it will be of contrasting color and the writing may be easily read by those not blind. The mucilage is added in order to make the material suitably adhesive. It is found that 50 sugar renders the material somewhat adhesive but not sufficiently so. Furthermore, the addition of mucilage prevents the material from cracking when dry and allows the paper upon which the writing is made 55 to be folded or rolled.

Any one possessed of the ordinary knowl-

edge of writing may easily write with the material and easily read such writing, since it appears to the eye much as writing in ordinary ink does. The blind may easily 60 read such writing, since the letters are very materially raised and very perceptible to the touch and the forms thereof may be readily made out by passing the fingers lightly over the same.

65 Writing with my improved material may be read quickly as well by the blind as by those still possessed of sight, who will read it in the ordinary manner. My improvements are therefore specially suitable to those 70 who become blind in later life and who have not specific knowledge of the methods for writing for the blind which have heretofore been commonly used. Such writing which has heretofore been used for the blind 75 is not readable by those who are possessed of sight and read only in the ordinary manner. It will also be evident that my improvements may be used for the purposes described in connection with other markings 80 besides letters. For instance, my improved writing material is also applicable to the making of pictures, geometrical figures or other drawings to be used by the blind, or other persons in communicating with them.

85 My improved writing material is very stable and I have found by experience that it will keep for a year or more without deteriorating in any way. It will readily flow when a suitable pen is used and dries 90 within a few minutes, so that it is specially advantageous for letter writing. As far as I am aware, I am the first to provide a writing material which, when deposited upon paper in the usual manner, will leave 95 the characters sufficiently raised so that they may be easily read by the blind.

Although I have described my improved material in great detail, nevertheless, I do not desire to be limited to the specific components and amounts thereof, since many variations therein may be made well within the spirit and scope of my invention.

100 Having fully and clearly described my improvements, what I claim as new and desire to secure by Letters Patent is:

110 1. A writing material, having in combination one part sugar, one part flour, one part water, one part mucilage and one part black ink.

2. A fluid writing material, having in combination sugar, flour, water and muci-

lage, or their equivalents, substantially as described, and a suitable coloring material.

3. A fluid writing material, having in combination sugar, flour, water and mucilage, or their equivalents, the parts being substantially as one to one, and a suitable coloring material.

In testimony whereof, I have signed my name to this specification, in the presence of two subscribing witnesses.

MARIE F. C. STOCKMANN.

Witnesses:

GORHAM CROSBY,
EDWIN SEGER.
